UNITED STATES PATENT OFFICE.

VINCENT G. APPLE, OF DAYTON, OHIO, ASSIGNOR TO DAYTON ELECTRICAL MANUFACTURING CO., A CORPORATION OF OHIO.

CENTRIFUGAL GOVERNOR.

No. 868,750.

Specification of Letters Patent.

Patented Oct. 22, 1907.

Application filed April 20, 1907. Serial No. 369,207.

To all whom it may concern:

Be it known that I, VINCENT G. APPLE, a citizen of the United States, residing at Dayton, in the county of Montgomery and State of Ohio, have invented certain new and useful Improvements in Centrifugal Governors, of which the following is a specification.

My invention relates to improvements in centrifugal governors, and has for its general object to provide an improved governor adapted for association with a variable speed or high speed prime mover, to act to transmit to an element to be driven a practically uniform, constant and relatively low speed of rotation.

One of the particular objects of my invention is to provide a governor of this type which is self-contained, wherein the rotating parts run wholly upon bearings constituting part of the self-contained structure.

A further object of my invention is to provide a construction wherein all of the bearing parts are inclosed and may run in grease or other lubricant.

Still another object of my invention is to provide a governor wherein the adjustment of the parts to effect increase or decrease in the speed of the driven element may be effected while the governor is in operation, and further, without materially changing the frictional resistance offered by the parts in rotation.

A yet further object of my invention is to provide a construction which is simple, efficient, readily taken apart and assembled, and capable of instant adjustment to vary the speed imparted to the driven element.

Other and further objects of my invention will become apparent to those skilled in the art from the following description taken in conjunction with the accompanying drawings; wherein,

Figure 1 is a central vertical, longitudinal section through a governor embodying my invention; Fig. 2 is a transverse section on line 2--2 of Fig. 1, and, Fig. 3 is a cross section on line 3--3 of Fig. 1.

Throughout said several views like numerals of reference refer always to like parts.

In the drawing 5 indicates a casing, which may be a casting of suitable shape, providing a central chamber 6, wherein the governor weights may move. The front end wall 7, of the casing, is recessed suitably to receive a ball bearing structure 8, whereof 9 is an outer annulus, seated in a recess in the casing wall; 9' is an inner annulus affording a central shaft passage, and 10--10 are the balls, interposed between said annuli, and positioned by suitable retainers 10', such structure representing a typical ball bearing of the self-contained type, suitable for the purpose to be described. I prefer further that a packing 11 should be arranged between the inner annulus or race 9, and the end wall of

the casing, which is apertured only sufficiently for the reception of a shaft.

12 indicates the thickened rear wall of the casing 55 internally screw-threaded as at 13 to receive an adjusting head 14, such head being provided with a screw threaded portion 15 and an enlarged handle portion 16 surrounding a central aperture 17, for the reception of a casing of a flexible shaft, such as that indicated in 60 dotted lines at *a* in the drawing, to which shaft casing the adjusting head may be secured against rotation by set screws 18, sunk in threaded apertures 19 which may also serve as spanner holes. In the adjusting head 14 is mounted a rear ball bearing 20 comprising an outer 65 annulus 21, an inner annulus 21', and interposed balls 22, and retainers 22', the ball bearing structure being preferably of a type which is self-supporting, as in the case of the ball bearing 8 at the front end of the structure. 70

Through the alining annuli 9' and 21', of the front and rear bearings, passes a shaft 23, which extends beyond the front end of the casing 5, and has secured to its projecting end a pulley 24, illustrated as a beveled friction pulley. 75

While the pulley may be secured to the shaft in any approved manner, I illustrate an advantageous construction to this end, involving a pin 25 extending transversely through the shaft and projecting on both sides thereof, the pulley 24 having in its hub slots 26 80 which embrace the projecting ends of the pins 25 and hold the pulley against rotation, the pulley being held against slipping axially from engagement with the pin 25 by means of a screw 26 taking axially into the shaft through the front face of the pulley. 85

30 indicates a collar secured to the shaft 23 by pin 31 said collar being flattened on opposite sides and having pivoted thereto governor weights 32--32 of semi-annular shape in cross section, and provided with curved arms 33, adapted to constitute eccentric or cam 90 levers, as hereinafter described, pivoted on pins 34 taking into the flat surfaces of the collar 30, heretofore described. Between the front end of the collar 30 and the member 9' of the front ball bearing, is interposed a plate 35, preferably presenting a flat surface of considerable extent toward the collar 30 and centrally thickened to present a bearing surface at its forward end to the inner race 9' only of the front ball bearing structure 8. 95

A coiled spring, 36, surrounds the shaft 23 and passes 100 within the space inclosed by the two semi-annular weights 32, to find bearing at opposite ends against the collar 30 and the inner race 21', of the rear wall bearing 20 respectively.

The shaft 23 is provided with a telescoping member, with respect to which it may move axially only, and to this end the rear end of said shaft is made tubular, the recess 37 therein being provided with internal 5 feathers 38, to interfit in grooves 40 in a telescoping shaft section 39 to which is suitably secured a coupling head 41, adapted to receive and be suitably fastened to a flexible shaft or other suitable part to be driven, substantially as indicated in dotted lines at *b*.

10 In use my governor is adapted for the transmission to shaft element 23, and the other connected elements to be driven, substantially uniform speed of rotation, precisely determinable by adjustment of the governor, from a high speed or variable speed time mover, where- 15 with the pulley 24 is arranged for coaction. It will be seen that if pulley 24 be pressed against the prime mover, such as a fly-wheel of the variable speed gas engine, so that said pulley is rotated, the rotation is imparted to the shaft 23, through the telescoping shaft 20 section 39 to the other elements to be driven connected therewith, for instance, the flexible power shaft *b*, indicated in dotted lines. Rotation of the shaft 23 carrying with it the governor weights 32, causes said governor weights to fly outward so that their cam-shaped 25 carrying arms 33 to press against the bearing plate 35 to exert a tendency to move the shaft 23 rearwardly, against the tension of spring 36. When the speed of rotation of the shaft 23 and the governor proper is such that the spring 36 is unable to resist the thrust caused 30 by the action of the governor arms 33 upon plate 35, the shaft 23 is moved bodily rearward withdrawing pulley 24 from contact with the prime mover, as shown, until the speed of rotation is so reduced that spring 36 may overcome the thrust occasioned by the centrifugal 35 action of the governor and push the shaft with its pulley 24 forward for effective connection with the prime mover again. In practice it will be well understood that with a given adjustment of the spring 36, a practically constant speed of the shaft 23 and its connected 40 elements to be driven is secured, as this general principle of governing is well known.

It will be seen from the construction disclosed that the tension of spring 36 may be adjusted by rotation of the adjusting head 14, which screws said head 14 and 45 the ball bearing carried thereby toward or from the governor. It will further be noted that the spring 36 at the rear end and the wear plate 35 at the front end, both bear against members of anti-friction bearing rotatable with the shaft, so that increase and decrease of 50 the tension of spring 36 results in no perceptible change in the frictional loss of power in the governor. Further it will be seen that the division of the telescoping shaft section admits of sliding movement of the shaft member 23 without disturbance of the relation of the 55 connection of the shaft to the extraneous, such as the flexible shaft illustrated in dotted lines at *b*.

While I have herein described in some detail a specific embodiment of my invention, which I have found in actual practice to be advantageous, it will be apparent to those skilled in the art that numerous modifications in the specific embodiment may be made without departure from the spirit and scope, and I do not desire, therefore, to be understood as limiting my

invention in its broader aspect to the specific devices shown and described.

Having thus described my invention, what I claim and desire to secure by Letters Patent, of the United States, is:

1. In a governing appliance, a frame or casing, a shaft supported thereby for axial movement, separated axially-stationary parts mounted for rotation with the shaft, a weight carried by the shaft, arranged when moved by centrifugal action to act upon one axially-stationary part to move the shaft axially, and a spring opposing the action of said weight bearing on the other axially-stationary part. 75

2. In a governing appliance, a frame or casing, a shaft, opposing end bearings for the shaft, comprising parts rotatable with the shaft, parts positioned by the casing, and interposed anti-friction parts, and a centrifugal governor carried by said shaft between said bearings, comprising 80 parts arranged to exert a cam action upon a part of one of said bearings rotatable with the shaft, and a spring opposing said cam action, exerting its thrust upon that member of the opposite bearing rotatable with the shaft.

3. In a governing appliance, a containing casing providing opposite end bearings, one of which is adjustable axially of the casing, a shaft mounted in said bearings, a governor carried by said shaft between said bearings, and comprising an adjustable spring, coacting with one of said bearings for adjustment as to tension by axial ad- 85 justment of said bearing. 90

4. In a governing appliance, a frame or casing, a shaft supported thereby for axial movement, separated parts positioned axially by the frame and rotatable with the shaft, one of said parts being adjustable in the frame with respect to the other, and a governor on the shaft between said parts, comprising a weight arranged when moved by centrifugal action to exert a cam action on one said part to move the shaft axially, and a spring opposing the action of said weight bearing on the other said part. 95

5. In a governing appliance, a casing providing a central chamber, anti-friction bearings closing opposite ends of said chamber, one of said bearings being axially adjustable, a main shaft member extending through the casing finding bearing at opposite ends in said anti-friction bearings, an extension shaft member telescoping with the said main shaft, and a governor carried by the main shaft arranged to impart axial movements to said main shaft. 105

6. In a governor appliance, a casing providing a central chamber, anti-friction bearings at opposite ends, each comprising a central part for rotation with the shaft, a main shaft engaging said rotatable bearing parts, and a governor carried by the said shaft between said bearings, comprising weights arranged to exert a cam action upon the rotatable part of one bearing to axially move the 115 shaft, and a spring arranged to exert its thrust against the rotatable part of the opposite bearing, for resisting the action of the governor weights, and means accessible from the exterior of the casing for axially adjusting the last said bearing. 120

7. In a governor appliance, a casing provided at its front end with a bearing, and at its rear end with screw-threaded apertures, an adjusting head closing said end of the aperture provided with a central bearing, a shaft passing through said front and rear bearings, a governor carried by the shaft between said bearings and arranged when in rotation to exert a tendency to move said shaft rearward axially of the casing, said governor comprising a spring for resisting such movement of the shaft, at its rear end abutting against a part carried by and adjustable with said adjusting head. 125

8. In a governor of the character described, a casing provided with anti-friction bearings at opposite ends, an adjusting head carrying the rear bearing, having an enlarged central aperture in rear of said bearing, a main shaft section mounted in said bearings, a pulley on the front end of said shaft, an extension shaft section telescoping therein and rotatable therewith, and a governor comprising semi-annular weights 32 and cam arms 33, 135

mounted for rotation with the main shaft section, to tend to move said shaft rearwardly under the influence of centrifugal action, and comprising also a spring 36 interposed between a part connected with the main shaft section 5 and said adjusting head.

9. In a governing appliance, a frame, a main shaft member axially movable therein, a governor connected with said shaft member to axially move it, and an extension shaft member telescoping with said main shaft member 10 and longitudinally movable independently of the governor.

10. In a governing appliance, a frame, a main shaft member axially movable therein, a friction gear device

carried by said shaft member, a governor connected with said shaft member for axially moving it, an axially-stationary transmission part, and an extensible connection 15 between the last said part and said shaft-member uniting them for rotation.

In testimony whereof I hereunto set my hand in the presence of two witnesses.

VINCENT G. APPLE.
